Des. 215,224
Patented Sept. 16, 1969

215,224

RIDING TOY

Irwin Cohn, 746 West St., Leominster, Mass. 01453

Filed Nov. 12, 1968, Ser. No. 14,407

Term of patent 3½ years

Int. Cl. D21—02

U.S. Cl. D34—15

FIG. 1 is a front perspective view of a riding toy embodying my new design.

FIG. 2 is a cross-sectional view taken on line 2—2 of FIG. 1.

FIG. 3 is a top plan view of said toy.

FIG. 4 is a front end view thereof; and

FIG. 5 is a rear end view thereof.

I claim:

The ornamental design for a riding toy, substantially as shown.
